CLAIM

The ornamental design for a touch pad, as shown and described.

DESCRIPTION

FIG. 1 is a front left perspective view of a touch pad showing my new design;

FIG. 2 is a top view of the design shown in FIG. 1;

FIG. 3 is a bottom view of the design shown in FIG. 1;

FIG. 4 is a left side view of the design shown in FIG. 1;

FIG. 5 is a right side view of the design shown in FIG. 1;

FIG. 6 is a front view of the design shown in FIG. 1; and,

FIG. 7 is a back view of the design shown in FIG. 1.

1 Claim, 7 Drawing Sheets
